UNITED STATES PATENT OFFICE

2,661,908

AIR SWEPT TUBE MILL WITH POCKETED LINER STRUCTURE FOR AUTOMATIC CLASSIFICATION OF GRINDING BODIES AND GROUND MATERIAL

Jean A. Slegten, Brussels, Belgium

Application May 8, 1950, Serial No. 160,783

1 Claim. (Cl. 241—45)

1

This invention relates to the comminution of materials occurring in a substantial range of particle size and is concerned more particularly with crushing and grinding, in which the material to be reduced to the desired state of fineness is subjected to classifying as an incident to grinding. The method may be practiced most advantageously in a mill of the tube type, which includes a cylindrical chamber rotating on a substantially horizontal axis and provided at one end with an inlet for material to be treated and, at the other, with means for discharging the finished material. A mill for practicing the method is of novel construction and the invention includes the new mill.

Heretofore, various methods of crushing or grinding material of the type described have been employed, such as that employed in a conical ball mill wherein automatic classification according to particle size is produced by the conical slope of the entire mill drum and the rotation thereof. In this type of grinding or crushing, the coarse material lies toward or adjacent the inlet of the mill, because of the slope of the mill walls, and the particles of material diminish in size toward the apex of the conical portion. The material being ground is classified because of the sliding rotating movement of the particles within the conical drum, the heavier particles moving toward the base of the cone by agitation and the force of gravity. The problem of removing the fines as soon as possible after they are formed is rather difficult because they are mixed with the coarser fractions throughout the grinding zone and are subject to removal only after they arrive near the apex of the cone. If a current of air is passed through the interior of the mill for the purpose of removing the material in its finished ground state, a very low percentage of the fines will be picked up by the current near the base of the cone, but the air will pick up the largest percentage of the fines at the discharge end or apex of the mill where their accumulation is greatest.

It is, accordingly, among the purposes of this invention to provide a mill that will automatically classify the grinding bodies by reason of the construction of the mill liner, and will also effect automatic classification of the material by the cooperation between the mill liner pockets and a current of air passing through the mill.

In general, the apparatus of the invention comprises a generally horizontally disposed elongated cylindrical chamber, having an inlet at one end for the material to be ground, and

an outlet at the other end, through which the ground material can be discharged. The mill cylinder is divided into two main chambers, the first of which is a crushing chamber at the inlet end of the mill. The other chamber of the mill is a grinding chamber, or attrition mill, and it is provided with liner sections of frusto-conical shape abutting each other to form the grinding surface and also to provide a means for automatically classifying the grinding media. The surface of each section exposed to the material being ground is provided with a series of openings with a pocket beneath each opening. A current of air is passed through the mill for the purpose of classifying the material being ground and for the further purpose of discharging part of the material of a desired fineness through the material outlet. The material enters through the inlet opening into the crushing chamber of the mill, where mixed media operate the crushing. As the material flows into the grinding chamber of the mill containing the individual frusto-conical liner sections, the final comminution begins. Because of the sloping surfaces of the liners, the grinding bodies will automatically be classified with the larger bodies located in the initial grinding zone of the grinding chamber and the remainder of the bodies progressively decreasing in size toward the discharge end and with the smallest bodies lying adjacent the material outlet. Similarly, the combined action of the liner pockets and air stream will classify the material being ground according to particle size with the larger particles in the initial grinding zone of the mill and the particles progressively decreasing in size toward the discharge end.

As the material is being ground in any part of the grinding chamber, fines will be produced as a result of the fracturing of the larger particles of material. These fines will enter into those pockets of the individual liner sections, which lie beneath the material. As the rotation continues, the filled pockets rise to the upper part of the mill, where the material contained in the pockets is discharged from the pockets and falls toward the bottom of the cylinder. In such fall, the material passes through the current of air flowing through the grinding chamber.

During their chute, the particles undergo a gravimetric separation, the larger fall with a higher speed and more or less vertically, while the tiniest are deflected by the mill sweeping air and entrained in direction of the outlet before they drop on the grinding media. An energetic sizing of the particles takes place, the smallest

progressing quicker towards the smaller grinding media where they are ground more efficiently and so on until they reach the mill end, in the flow of material or entrained to the dust collector. The larger particles fall practically vertically and remain under the action of the bigger steel media, until their specific surface is sufficiently increased to make them sensible to the axial air current, pulling them forward in such the greater steps as they are tinier.

By controlling the quantity or speed of cooling air, the progression of the fine particles can be changed and at the same time the average size and the fineness of the final ground product.

From the use of liners according to the invention, results an important saving in power absorbed per barrel of ground material. The temperature rise is lower and also steel wear and maintenance. Grinding efficiency increases for two causes; the permanent elimination of fines cushioning the attritive action and the continuous assorting of medium and particle sizes for top grinding efficiency. It has been proven that the relation between sizes of particles and media affects the efficiency in such range as from 1 to 5, keeping within conditions common in the industrial grinding practice.

In order that my invention may be clearly understood, it will be described with reference to the accompanying drawings, in which:

Fig. 1 is a vertical diagrammatic view, partly in section and with parts omitted, of a preferred form of apparatus for the practice of the new method;

Fig. 2 is a longitudinal cross-section through the center line of the mill;

Fig. 3 is a partial cross-section of the mill showing the classifying chambers of the tube mill;

Fig. 4 is a view similar to Fig. 3 showing a modified form of the liner chambers;

Fig. 5 is a longitudinal cross-sectional view of the tube mill liners on an enlarged scale.

Referring to Fig. 1, a bin or hopper 1 controlled by a suitable valve 2 contains the raw material to be ground. A material conveying tube 3 is connected at one end to the feeder and, at the other end, to an air admission valve 4 positioned between the material discharge tube 3 and the tube mill material inlet 5. The tube 3 is provided at its ends with hollow trunnions 7, 8, supported in bearings 9, 10, respectively, the passage through trunnion 7 forming the material inlet 5 and the passage 11 through trunnion 8 forming the material outlet.

The tube mill is divided into two main chambers 12, 13 and the initial crushing of the raw material takes place in chamber 12. The second main chamber 13 is the grinding chamber and it is provided with a grinding surface comprised of individual frusto-conical sections 19, each section abutting the adjacent section to produce a series of individual frusto-conical zones throughout the grinding chamber 13. A grid 9 separates the crushing chamber from the grinding chamber and maintains the crushing elements in the crushing chamber at all times, while permitting the raw material after a desired crushing action to be passed into the grinding chamber.

Each liner section 19 is made up of individual elements 20 which, as shown in Fig. 3, are of shell construction so that there is a pocket 21 having an opening 22 between adjacent elements around the inner periphery of the tube mill.

A fan 23 is provided to produce a current of air flowing through the mill 6 for the purpose of cooling the mill, and to classify and entrain, according to their individual size, the particles dropping from the pockets. The fan is equipped with a suction line 24 connected to the outlet sieve 25, which receives the material discharged from the tube mill through outlet 11 and has a discharge spout 26, through which material removed from the air is discharged into a receiver 27 whence it is conveyed to any desired point for further processing. As the air leaves the sieve 25 through the suction line 24, some of the finely ground material is still entrained in the air stream and the air and material are passed through a dust collector 28, wherein the material is completely removed from the air. This material is conveyed from separator 28 through a discharge spout 29 to discharge spout 26, and the exhaust air from the separator 28 is vented through a vent stack 30 to the atmosphere.

The mill 6 is rotated by any convenient means, such as a gear 35 attached to the mill casing and driven through a geared shaft 36 by any convenient conventional prime mover, not shown.

In the operation of the apparatus, the fan 23 is started as soon as the mill starts to rotate, and it maintains a current of air through the mill system. The air enters the mill system through the air admission and the material inlet 5, flows through the two chambers 12 and 13, issues from the mill through the material outlet 11, passes through the sieve 25 and the dust collector 28, and exhausts from the mill system through the vent stack 30.

The material from hopper 1 passes through the discharge tube 3 and enters the mill through the material inlet 5. As the material enters the chamber 12, the crushing takes place. The material is progressively reduced in size by the mixed grinding bodies, after which it enters the grinding chamber 13 for the final phase of comminution.

The grinding bodies in the grinding chamber 13 are automatically classified by the inherent classifying action of the frusto-conical liner sections, with the largest of the grinding bodies lying adjacent to the inlet of the grinding chamber and the bodies gradually decreasing in size, so that the smallest bodies lie adjacent the material outlet of the mill.

An automatic classification according to particle size of the material to be ground, is produced by the combined action of the pockets 21 of the liner sections and the current of air flowing through the grinding chamber.

In each zone of the grinding chamber, fine material is produced by the breaking up of the larger particles and the finest particles are removed from the zone, in which they were produced, as soon after they are formed as possible. This result is achieved as follows. As the particular pocket is rotating beneath the material charge in the mill, the ground material enters and fills the pocket. When the pocket is elevated to the upper section of the mill, the material in the pocket flows out of the pocket opening and falls toward the bottom of the mill through the current of air flowing through the mill. The material, that has been ground to a sufficient fineness, is entrained in the air stream and carried towards the mill end with the air, and the heavier particles falling faster remain behind in the grinding zone in presence

of relatively big grinding bodies more appropriate for further grinding of heavier particles.

The ground material passes through the outlet 11 into the sieve 25 and further into the receiver 27 whence it is conveyed elsewhere for further processing. The current of air leaving the sieve 25 through the tube 24 carries with it a certain amount of fine material, which is separated from the air in the dust collector 28 and discharged through tube 29, while the air 10 passes out through the vent stack 30.

A modified form of liner section is shown in Fig. 4, the section being made up of individual elements 34 spaced to provide pockets 33 having openings 31 of substantially the same width as the pockets. Within each pocket can be mounted a screen 32 overlying the pocket opening and provided with openings of the desired size to restrict the size of ground material which may enter the pockets and thereby avoid possible clogging of the openings by particles of larger sizes.

I claim:

A mill for crushing and grinding material, which comprises an elongated cylindrical member containing a crushing chamber and a grinding chamber adjacent each other and arranged for free flow of material from the crushing chamber into the grinding chamber, an inlet for admission of material into the crushing chamber, an outlet for material from the grinding chamber, means for rotating the cylindrical member, a series of frusto-conical liners in the grinding chamber, grinding bodies on the liners, the grinding bodies on the successive liners diminishing in size progressively toward the material outlet, means for causing a current of air to enter the crushing chamber through the

inlet, flow through the two chambers, and exhaust through the outlet, and a plurality of pockets in each liner each having an opening through which ground material may enter the pocket, when the pocket is at the bottom of the grinding chamber, and may be discharged therefrom when the pocket is at an upper portion of the grinding chamber, the material discharged from each pocket entering the air stream, screening means extending across the openings into said pockets to restrict the size of ground material which may enter the pockets, whereby some sufficiently ground material is carried out of the chamber and insufficiently ground particles are advanced and are deposited on the frusto-conical liners nearer the outlet than the liner containing the pocket from which they were discharged.
